Primary Examiner — Cynthia M. Chin(74) *Attorney, Agent, or Firm* — Carlson, Gaskey & Olds, P.C.**CLAIM**

The ornamental design for a floatation device for vessel, as shown and described.

DESCRIPTION

FIG. 1 is a perspective view of a floating device for a vessel; FIG. 2 is a front view of the floatation device for vessel of FIG. 1;

FIG. 3 is a back view of the floatation device for vessel of FIG. 1;

FIG. 4 is a first side view of the floatation device for vessel of FIG. 1;

FIG. 5 is a second side view of the floatation device for vessel of FIG. 1;

FIG. 6 is a top view of the floatation device for vessel of FIG. 1; and,

FIG. 7 is a bottom view of the floatation device for vessel of FIG. 1.

The broken lines shown are included for the purpose of illustrating portions of the article which form no part of the claimed design.
